ABSTRACT OF THE DISCLOSURE

This disclosure relates to a dirigible catheter having means defining a lumen with continuous smooth walls between the proximal and distal ends. The distal end is guidable through 360° by means of guide lines extending along the length of the catheter and differentially operated in pairs. Also disclosed is a magnetic force producing means to also differentially operate the guide lines in pairs.

This invention relates to catheters, and more particularly relates to dirigible catheters.

A catheter is basically a tube-like member insertable into a body passage or cavity which may be used for drawing off samples, or for other medical purposes. This invention relates to such devices and provides a new and improved catheter which is guidable through 360 degrees.

Catheters which have been capable of some guidance in direction of the distal end from the proximal end have heretofore been proposed. Such proposed guidance was usually accomplished by one tensioning member in the form of a wire or cord which extended along the length of the catheter within its inner channel or bore, was attached adjacent the distal end of the catheter, and tensioning the cord from the proximal end of the catheter would bend the tip or distal end of the catheter in one direction.

Additionally, some catheters have been proposed which require such a tensioning cord as a guide means but offset the bore of the catheter. Such construction resulted in extremely thick walls of the catheter and, therefore, reduced the bore thereof and its usefulness.

A catheter must be highly flexible so that it can be turned upon itself, yet sufficiently rigid to be pushed from its proximal end without kinking upon itself. Its external diameter is limited both by the passage in which it must be inserted and by the requirements for strength and longitudinal rigidity required for insertion and manipulation.

The present invention provides a new and improved thin-walled catheter which has a high ratio of bore or lumen dimension to overall diameter. The structure of this catheter is such that both the outer walls and the inner walls are smooth and cylindrical, and the bore is concentric with the outer cylindrical walls. However, the walls have such strength as to receive a plurality of tension means therein to allow the distal end thereof to be guided from the proximal end through 360 degrees freedom of motion.

Moreover, the construction is such that the guide lines may be simultaneously manipulated to easily guide the distal end of the catheter. The structure is further such that the walls may be made thin to maximize the ratio of the external diameter to the internal diameter. The invention further provides a catheter having a continuous bore of constant diameter concentric with the outer walls and having no obstructions therein which would hinder maximum utilization of the catheter.

Accordingly, an object of this invention is to provide a new and improved catheter.

Another object of this invention is to provide a new and improved catheter having an increased ratio of internal diameter to external diameter.

2

A further object of this invention is to provide a new and improved catheter having a distal end which is dirigible through 360 degrees of motion.

Another object of this invention is to provide new and improved means for guiding the distal end of a catheter from the proximal end thereof.

Further objects and advantages of the invention will in part be pointed out and in part be made apparent from the following description.

The features of the invention which are believed to be novel are set forth with particularity and distinctly claimed in the concluding portion of this specification. However, the invention both as to its organization and operation, together with further objects and advantages thereof may best be appreciated by reference to the following detailed description taken in conjunction with the drawings, in which:

FIG. 1 is a view in longitudinal section of a catheter embodying the invention;

20 FIG. 2 is a sectional view seen in the plane of lines 2—2 of FIG. 1;

FIG. 3 is a view of a catheter embodying the invention together with the guidance mechanism therefor;

25 FIG. 4 is an enlarged view of the operating mechanism of the catheter of FIG. 3 shown partly in section;

FIG. 5 is a view seen in the plane of lines 5—5 of FIG. 4;

FIG. 6 is a view seen in the plane of lines 6—6 of FIG. 4;

30 FIG. 7 is an enlarged view of a portion of the operating mechanism shown in FIG. 4;

FIG. 8 is a sectional view seen in the plane of lines 8—8 of FIG. 7;

FIG. 9 is a view in half section of another operating mechanism for the catheter of FIG. 1;

FIG. 10 is a sectional view seen in the plane of lines 10—10 of FIG. 9;

FIG. 11 is a view in section of a portion of the operating mechanism of FIG. 9; and

40 FIG. 12 is a schematic diagram showing the circuit connections for the operation of the mechanism of FIG. 9.

A catheter embodying the invention is generally indicated by the reference numeral 10 and comprises an outer cylindrical wall member 11 which is continuous along 45 the length of the catheter 10. At the distal end 12 of catheter 10 is a tip or end piece 13 of fairly rigid material having an inwardly directed flange-like portion 14 which fits over the end of the inner catheter tube 15, and which further has a cylindrical portion 16 surrounding the inner catheter tube 15 at the distal end thereof and which is bonded thereto. The member 13 further has a flange 17 thereon which receives guiding or tensioning cords 18a, 18b, 18c and 18d. These cords or lines are fastened to flange 17 to prevent being pulled therefrom, as by enlargement of the ends thereof by knotting of end pieces attached thereto. The cords extend through tube-like members, 19a, 19b, 19c and 19d, disposed at 90 degrees with respect to each other within the catheter body. A nose piece 20 is disposed about member 13 and extends back to a body member 21. Member 20 may be recessed as at 55 22 to enhance freedom of movement of the cords 18. Body member 21 may be formed with a shoulder 23 adapted to receive thereon the end of nose piece 20, and provide a continuous outer diameter therewith.

The catheter 10 is assembled by disposing tubes 19a and 19b about inner catheter tube 15 at 90 degrees around the circumference of tube 15. This assembly is then molded within member 21 which is of a suitable flexible material. One such material which has been found to have been satisfactory is a silicone compound RTV 11 of the General Electric Company. The inner tube 15 and tubes 19a—

19d are chosen to be flexible, and suitable materials have been found to be polyethylene or vinyl. During this molding operation a reinforcing sleeve of a suitable mesh material **24** is preferably disposed about the catheter tube **15** and the guide tubes **19a-19d** and molded within member **21** to provide reinforcing if deemed necessary.

The member **13** is then fitted over the distal end of tube **15** and the guide or tension cords **18** may be attached and threaded through tubes **19**. Member **20**, which has previously been molded of similar compound as member **21**, is then fitted over member **13** and extended into the shoulder **23** on member **21**. Then the outer tubing **11** which has been separately molded is slipped over members **20** and **21** to provide a smooth outer surface which is continuous throughout its length.

This construction provides a catheter which is continuous and of constant cross-section throughout its length except for the rounded distal end **12**. Further, the inner tube **15** is of constant cross-section throughout its length with no obstructions therein and defines the inner catheter passage or lumen **26**.

The catheter tube described may be varied in length from less than one foot to more than thirty feet, depending upon its usages which may be to inject radiopaque dyes quickly to points where lesions are suspected. Barium can be squirted directly in the region of the duodenal bulb, or the ascending colon. The catheter is further ideal for transporting a highly flexible, but rather unwieldy, fiberscope. For example, a catheter could be passed into the tracheobronchial tree and with the fiberscope, a suspected epithelial lesion could be located. Furthermore, when the catheter is in the proper position, suction could be applied and cells can be aspirated for a cytological examination.

The cross-sectional diameter may vary from between one-eighth inch up to two inches, again depending upon its desired use. The inner diameter will vary correspondingly, but will generally be about sixty percent or more of the outer diameter.

The materials of the catheter tube are made of flexible compounds such that it can be bent and turned on itself to make right angle turns and conform to pretzel configurations. Its flexibility range is such that it is sufficiently rigid to be pushed from its proximal portions without kinking on itself, and at the same time flexible enough to make the above-mentioned bends. The specific flexibility of the material will vary depending on its intended use. The previously mentioned General Electric Company RTV 11 silicone compound has a durometer of 48. The catheter tube itself is not subjected to tension greater than that required to pull or push it. The guide lines **18** running within its walls may be subjected to approximately twenty pounds of pull, depending upon the use of the catheter. These guide lines **18** may be made of wire, nylon, surgical silk or other suitable materials. It has been determined that the above-mentioned material can be autoclaved at 250 degrees Fahrenheit for forty-five minutes, which is more than sufficient to assure its sterility.

Returning to FIGS. 1 and 2, it may be seen that tensioning one or more of the guide cords **18** will produce bending of the distal end of the catheter **10** as represented by the broken line **27**. For example, the bending of the distal end shown in FIG. 1 may result from merely applying tension to the 180 degree line **18c** which would exert a pull downwardly as shown in FIG. 1 on the flange **17** of member **13**. By selectively tensioning different ones of lines **18a-18d** the distal end may be directed in any direction throughout 360 degrees with respect to a plane perpendicular to the axes thereof.

Reference is now made to FIG. 3 which shows the catheter **10** mounted to a manipulating device **30** which contains a mechanism for selectively operating the cords **18a-18d**. The manipulating device is exemplified in the form of a member having a pistol grip **31** which has a

passage **32** defined therethrough which is coaxial and of essentially the same size as lumen **26**.

The catheter tube **11** is coupled to the assembly **31** by means of an adaptor **34**. Adaptor **34** at one end thereof has longitudinally extending fingers **35** defined by longitudinally extending slits **36** therein, and is threaded at **37** to receive a chuck-like member **38**. Adaptor member **34** further includes a collar-like member **39** received in an undercut **40** therein which has internal threads **41** adapted to mate with threads **42** on the exterior of barrel **43**. To assemble the catheter tube to the handle and operating assembly, the lines **18a-18d** are connected to mating lines **18a'-18d'** extending from an operating mechanism, hereinafter described, as by means such as hook and eye connectors **44**. Then adaptor **34** is fitted to barrel **43** and has an intercocking fit as indicated at **45** therewith. Then the collar-like member **39** is threaded on to handle member **30** and the adaptor is made fast to handle **30**.

Then the catheter tube is pulled outwardly of adaptor **34** to tension the lines **18a-18d** so that there is no slack therein, and all lines are equally tensioned with the distal end of the catheter tube unbent. At this time, chuck-like member **38** is threaded tightly on to adaptor **34** so that the inclined portion **38a** of chuck-like member **38** rides up over fingers **35** and compresses fingers **35** about the catheter tube. This compression of the fingers **35** about catheter tube **11** holds it securely in place and prevents either longitudinal or rotational movement thereof with respect to barrel **43**.

The lumen of catheter **10** is now coaxially aligned with the passage **32** defined in barrel **43**.

Disposed within barrel **43** is a bushing or sleeve-like member **46** which acts as a guide for lines **18a'-18d'** extending from a guiding control mechanism **47**. The function of sleeve **46** is to space the guide lines **18a'-18d'** as they change from a generally inclined direction with respect to the lumen of the catheter to a direction which is parallel of the axis of the lumen of the catheter. This further provides a clear access to the lumen through the barrel **43**. This is more clearly shown in FIG. 6. It will be noted that the line **18a'** must cross passage **32** without adding an obstruction thereto. This is done by gently curving line **18a'** in a helical path about the bushing or sleeve **46**, and for this purpose such a path may be defined therein. In this manner, appropriately contoured passages may be defined in the exterior periphery thereof for any or all of line **18a'-18d'** as may be required.

The catheter guidance mechanism **47** is more clearly shown in FIGS. 6-8. This mechanism provides a means for guiding the distal end of the catheter through 360 degrees projected on one plane.

The lines or cords **18a'** and **18c'**, and **18b'** and **18d'** are in continuous pairs, each pair disposed about a wheel **55** which upon rotation thereof tensions one line of a pair and releases tension in the other line of the pair.

The guidance mechanism **47** comprises a base member in the form of a plate **49** having an aperture defined therethrough which receives a ball **50**. Ball **50** is rotatable in plate **49** and retained in position with respect thereto by upper and lower retaining plates **51** and **52**. Extending through ball **50** is a shaft **53** having a trimble-like end piece **54** adapted to receive a finger for manipulation of shaft **53**.

Shaft **53** extends through an opening **55** defined by two pairs of half ring members **56**, **57**; and **58**, **59**, disposed perpendicular to each other. Members **56** and **57** are secured at their ends to coaxial shafts **60** and **61** which are rotatably carried in brackets **62** and **63**, respectively, which are in turn carried on plate **49**. Similarly, members **58** and **59** are secured to shafts **64** and **65**, rotatably carried in brackets **66** and **67**, mounted on plate **49**.

Mounted to shafts **61** and **65** are gears **68** and **69**, respectively. Also rotatably carried in brackets **62** and **67** are shafts **70** and **71**, respectively. Mounted to shaft **70**

is a gear 72 in meshing engagement with gear 68. When gear 72 is driven by gear 68 it rotates a sheave or wheel 73. Mounted to shaft 71 is a gear 74 and wheel 75. When gear 69 rotates gear 74 it also rotates a sheave or wheel 75.

Disposed about wheel 73 are lines 18b' and 18d'. Disposed about wheel 75 are lines 18a' and 18c'.

In operation, it may be seen that when shaft 53 is manipulated it will act against one or both pairs of members 56, 57 or 58, 59 and produce rotation of one or both of shafts 61 and/or 65. This will produce resultant rotation of one or both of wheels 73 and 75. Wheel 73, about which is wound lines 18b and 18d, upon rotation thereof, will tension one of the lines and provide slack in the other of the lines. Similarly, rotation of wheel 75 will tension one of lines 18a or 18c and provide slack in the other of the lines. Therefore, any two of lines 18a through 18d residing at right angles to each other may be simultaneously tensioned to exert a pulling force on member 13 and, therefore, bend and guide the distal end of the catheter through 360 degrees.

It may thus be seen that this operating mechanism, while providing 360 degrees of motion at the distal end of the catheter tube, allows the guide lines which are 180 degrees apart to be tensioned and slacked simultaneously, and further provides that varying amounts of tension may be applied to the guide lines which are 90 degrees apart to bend and position the distal end of the catheter at any angle.

While the degree of motion has been spoken of as 360 degrees, it will be understood that this refers to 360 degrees in one plane which is perpendicular to the axis of the catheter in its relaxed position, and further provides for three-dimensional positioning of the distal end of the catheter with respect to such 360 degrees.

Other techniques of selectively tensioning one of a pair of the guide lines may be utilized. FIG. 9 shows an alternate embodiment which works on an electromagnetic principle. In FIG. 9 each of the lines 18a-18d are connected to the plungers 80a-80d of electromagnets having coils 81a-81d. Dependent upon the magnitude of energization of the coils, the plungers therein will either advance as shown in FIG. 9 or be retracted towards the left. Each of the electromagnets is disposed 90 degrees with respect to the axis of the catheter within a housing member 82 having a bore 83 coaxial with the catheter lumen.

The electromagnets are selectively energized through a mechanism similar to that shown in FIGS. 6-8. This mechanism is illustrated in FIG. 11 and like reference numerals to those used in FIGS. 6-8 identify like elements in FIG. 11. In the mechanism 84, the shaft 61 has mounted thereto the contact arm 85 of a potentiometer 86. The shaft 65 carries a contact arm 87 of a potentiometer 88.

The circuit connection to the potentiometers 86 and 88 with coils 81a-81d are shown in FIG. 12. It will be noted that the current from a source such as battery 89 is applied to both of the contact arms 85 and 87, and when these contact arms are on the midpoint of the resistance of potentiometers 86 and 88 all coils will be equally energized and the tension in all of lines 18a-18d will be equal. However, when the contact arms are displaced as shown in FIG. 12, coils 81a and 81b will receive more current than coils 81c and 81d, respectively. Therefore, lines 18a and 18d will be tensioned with respect to other lines and the distal end of the catheter will be guided in a quadrant defined by the lines 18a and 18b.

It may thus be seen that by proper manipulation of shaft 53 with one finger, the distal end of the catheter may be guided through 360 degrees, and provides continuous three-dimensional vectorial resolution to coordinate axes. Preferably, a pistol-type grip as illustrated is used to handle the manipulation assembly so that the distal end of the catheter may be guided through use of one finger.

The disclosed catheter may have many applications. For example, in radiology, the catheter provides a means by way of which radiopaque dyes can be injected quickly to points where lesions are suspected. The disclosed catheter is ideal for transporting the highly flexible, but rather unwieldy fiberscope. In another embodiment of the invention a fiberscope could be incorporated into the walls of the catheter and the catheter lumen would be then used for providing instrumentation. For example, the catheter with a built-in fiberscope could be passed into the tracheobronchial tree and a suspected epithelial lesion located. Then suction could be applied to the region in question and cells could be aspirated for cytological examination. Further, this catheter would be useful in pulmonary embolectomy. Once the disclosed catheter, for example, with a fiberscope therein is utilized to locate an embolus (cardiac catheterization and injection of radiopaque dye under fluoroscopy) a second catheter, the embolectomy catheter, which consists of a small plastic drill piece would be utilized to break up and drive the thrombus into the catheter. Suction applied at pressures greater than right ventricular systole would cause bits of thrombus to be sucked back through the embolectomy catheter. Additionally, the embolectomy catheter could be utilized for taking small samples which would be drawn back into the disclosed catheter.

From the foregoing disclosure, it may be seen that the objects of the invention set forth as well as those made apparent from the preceding description are efficiently attained. While presently preferred embodiments of the invention have been set forth for purposes of disclosure, other embodiments of the invention and modifications to the disclosed embodiments which do not depart from the spirit and scope of this invention may occur to others skilled in the art. Accordingly, the appended claims are intended to cover all embodiments of the invention as well as modifications to the disclosed embodiments of the invention which do not depart from the spirit and scope thereof.

What is claimed is:

1. A catheter comprising a flexible elongated tube having a proximal end and a distal end adapted to be inserted into a body passage, said tube having a continuously smooth outer surface and continuously smooth inner walls defining a continuous unobstructed passage from said proximal end to said distal end, a plurality of guide lines anchored adjacent the distal end of said tube and equiangularly between the walls defining the passage and the outer surface of the catheter, said lines being longitudinally movable with respect to said tube, said lines being four in number and disposed 90 degrees about said catheter, the lines 180 degrees apart forming a pair, to means for tensioning said lines including means for simultaneously tensioning one line of a pair and releasing tension in the other line of a pair.

2. The catheter of claim 1 wherein said catheter further comprises an inner tube defining the continuous passage and an outer tube defining said outer surface spaced from said inner tube, said lines being disposed about said inner tube, means secured to said inner tube adjacent the distal end thereof, and said lines being anchored to said coupling means.

3. The catheter of claim 1 wherein said means for tensioning comprises electromagnetically operated means connected to each of said lines, energizing means for said electromagnetically operated means, said energizing means being differentially connected so that as the tension in one of said lines of a pair is increased the tension in the other of the line of a pair is decreased.

4. An elongated tube-like member comprising an inner flexible tube member having a smooth, continuous inner wall, an outer flexible tube member disposed about said inner tube and having a smooth continuous outer surface, means coupling said tubes at the distal ends thereof, four guide lines disposed at 90 degrees with respect to each

other between said tubes and secured to said coupling means, and means for selectively tensioning two lines and releasing tension in the lines 180 degrees therefrom.

5. The apparatus of claim 4 wherein said coupling means comprises a member disposed about and secured to said inner tube and having an annular flange adapted to receive said lines.

6. A catheter comprising an elongated flexible tube member having proximal and distal ends, two pairs of force-producing lines extending along said member between said proximal and distal ends, the lines of said pairs being spaced substantially 180 degrees apart so that said flexible member may be caused to bend by exerting a force on one line of a pair and releasing force on the other line of a pair, electromagnetically operated force-producing means for each of said lines, means connecting each of said lines to one of said electromagnetically operated means, and energizing means for simultaneously operating two of said electromagnetically operated means to release force on one line of a pair and apply force to another line of a pair.

7. The apparatus of claim 6 further including means for simultaneously energizing all of said electromagnetically operated means in pairs.

8. The apparatus of claim 6 wherein said electromagnetically operated means comprise two pairs of electromagnets having magnetic elements movable in a direction and magnitude dependent on the strength of a magnetic field applied thereto, means for producing magnetic fields for each of said magnetic elements and means for simultaneously strengthening the field of one electromagnet of a pair and weakening the field of the other electromagnet of a pair.

5. The apparatus of claim 6 wherein said energizing means for each pair of lines includes a potentiometer having a resistance and contact arm, each pair of energizing means being connected to opposite ends of one potentiometer resistance and differentially energized therethrough dependent of the position of the contact arm on said resistance, and means connected to said contact arms to allow simultaneous and independent movement of the contact arm of each potentiometer.
